GOLF PUTTER

Robert J. Mader, Torrance, Calif., assignor to
Wilson Sporting Goods Co.

Filed Dec. 8, 1969, Ser. No. 20,392

Term of patent 14 years

Int. Cl. D21—03

U.S. Cl. D34—5

FIG. 1 is a perspective view of the putter taken from one side thereof, showing my new design,

FIG. 2 is a side elevation view of the putter head,

FIG. 3 is a top plan view of the putter head,

FIG. 4 is an end elevation view of the putter head,

FIG. 5 is a side elevation view of the putter taken from the side thereof opposite to that of the view of FIG. 2.

The shaft has been shown fragmentarily in FIGS. 1, 2, 3 and 4 for convenience of illustration.

I claim:

The ornamental design for a golf putter, as shown and described.
